EUGENE A. KUEN, OF CINCINNATI, OHIO, ASSIGNOR, BY MESNE ASSIGNMENTS, TO THE CORCORAN-VICTOR COMPANY, OF CINCINNATI, OHIO, A CORPORATION OF OHIO.

BUFFING-MACHINE.

1,234,351.

Specification of Letters Patent. Patented July 24, 1917.

Application filed April 17, 1916. Serial No. 91,633.

To all whom it may concern:

Be it known that I, EUGENE A. KUEN, a citizen of the United States, residing at Cincinnati, in the county of Hamilton and 5 State of Ohio, have invented certain new and useful Improvements in Buffing-Machines, of which the following is a specification.

The present exemplification of my invention 10 is a modification and elaboration of the invention shown, described and claimed in my companion application, Serial No. 91,632, filed April 17, 1916.

In the present exemplification, my invention 15 is applied in buffing the outer surface of a bowl-shaped or parabolic article, exemplified as the body of a lamp adapted to receive a parabolic reflector, the body being substantially of parabolic form having an 20 outwardly flaring end adjacent to its base.

It is the object of my invention to provide 25 means, in buffing machines, whereby the outer surfaces of bowl-shaped or parabolic formed articles may be buffed, that is, abraded or polished, by means of a buffing-wheel.

The invention consists in providing a head or heads arranged to have the article to be buffed applied thereto, and novel means for 30 causing movement of the head with relation to the buffing-wheel for causing the head to automatically shift according to its form with relation to the buffing-wheel for contact of successive points in its outer periphery with the buffing-wheel; further in novel 35 means whereby to rotate and to reciprocate the heads in a plurality of directions during the buffing operation; further, in novel means for yieldably mounting the head and 40 causing approach of the yieldably mounted head to operative position with relation to the buffing-wheel and recession of the head away from its operative position for the ready attachment of the bowl-shaped or 45 parabolic article to or removal of the same from the head or heads; further, in novel means whereby different shapes or contours of articles may be readily attached with 50 their inner faces about the head for coaction with the buffing-wheel; and, further, in novel means whereby the relation between a yieldable article-head and a buffing-wheel is 55 adjusted crosswise of the axial line of the article for coaction of the article with the buffing-wheel.

The invention will be further readily understood from the following description and claims, and from the drawings, in which latter:

Figure 1 represents a plan view of my 60 improved device.

Fig. 2 is a horizontal section taken on the line 2—2 of Fig. 3, representing the 65 gearing for rotating and reciprocating the heads.

Fig. 3 is a rear side elevation of my improved device.

Fig. 4 is a front side elevation of the 70 positioning means for the carriage of my improved device, showing the lever for shifting the carriage in full lines for operative position of the carriage, and in dotted lines for retractive position of the carriage.

Fig. 5 is a front end elevation of my 75 improved device, partly broken away, with the buffing-wheels and stands removed.

Fig. 6 is a vertical section of the head, taken on the line 6—6 of Fig. 5, showing the 80 article clamped thereon and in full lines in position when about to make contact with the buffing-wheel, and in dotted lines in positions assumed during the reciprocating movement in the buffing operation.

Fig. 7 is a plan view of the same taken in the direction of the line 7—7 of Fig. 6. 85

Fig. 8 is an axial section of the article-holder arranged for differently sized articles.

Fig. 9 is a cross-section taken on the line 9—9 of Fig. 6, showing a rear view of the 90 head, for showing the clamping means for the article.

Fig. 10 is a cross-sectional detail of the same taken on the line 10—10 of Fig. 9.

Fig. 11 is a longitudinal section of the 95 same taken on the line 11—11 of Fig. 10.

Fig. 12 is a detail in cross-section, on the line 12—12 of Fig. 3, showing the means for adjusting the crank controlling the reciprocating movements of the heads. 100

Fig. 13 is a horizontal section, taken on the line 13—13 of Fig. 3, showing the means for adjusting the saddle.

21 represents a frame, on which a saddle 105 22 is adjustable up and down, as by means of having a screw-rod 23 fixed to the saddle and depending therefrom, passing journal-wise into or through a bearing 24 in the frame, an adjusting nut 25, having threaded connection with the screw-rod, arranged to 110

be rotated by arms 26 for raising and lowering the saddle.

The saddle has up and down movement in guideways 27 between the saddle and frame.

5 Tie-rods 28 extend between the sides 29 of the frame, the sides being arranged to be clamped toward each other against the depending guides 30 of the saddle by means of nuts 31.

The saddle has guideways 34 on which a carriage 35 reciprocates. The carriage is arranged to support one or more heads 36, two of these heads being shown. Means are provided for reciprocating the head or heads 15 with relation to a buffering-wheel 37, two of these buffering-wheels being shown. It is to be understood that one of the heads and buffering-wheels may be employed in carrying out my invention, or a pair of them may, 20 as exemplified, be employed for simultaneous coöperating relations.

The head is arranged to have the article to be buffed applied thereto, and means are provided for rotating the article during the 25 buffering action, so that simultaneous reciprocation and rotation is imparted to the article during the buffering operation. The article is further arranged to yield with relation to the buffering-wheel during its reciprocation, so 30 that the successive points in the contour of the article may make contact with the buffering-wheel, and the article moved toward and from the buffering-wheel in its path of reciprocation, according to the contour of the article. I prefer that this approach and recession in the path of reciprocation shall be 35 resilient, and I have exemplified the same as accomplished by a counter balance.

The buffering-wheel, represented at 37, is arranged to rotate preferably in the direction of the arrow 38.

The article being buffed is exemplified as the body 39 of a headlight or vehicle lamp, such as used, for instance, on automobiles, 45 the body being of general parabolic form, comprising, for instance, a rounding 39^a at its apex end, an annular outwardly bulged portion 39^b, an annular outwardly flaring portion 39^c at its base end, there being an 50 inwardly bent annular portion 39^d between the annular outwardly bulged and annular outwardly flaring portions 39^b and 39^c, the body in the present exemplification terminating at its base end in a substantially cylindrical portion 39^e.

The article is exemplified as received about a holder 41, there being a suitable number of these holders of different sizes and shapes which are interchangeable on the head for 60 accommodating different sizes and different shapes of articles, as indicated by the dotted lines 39^f which represent the outer faces of different holders and the inner lines of bodies of different sizes and shapes. The 65 outer faces of the holders are arranged to

fit snugly in the inner faces of the formed sheet metal of which the body or article is composed.

These articles are usually formed out of a sheet of metal in a draw press by a drawing 70 operation. As a result of this operation the outer periphery of the body, especially at the portions 39^b and 39^c when drawn to shape, shows lines resulting from the stretching and shaping of the metal and lines occasioned by contact with the dies, the former showing as protuberances and the latter as streaks. The object of the buffering, which in the present instance is what might be termed an abrading action, accomplished by 75 the buffering-wheel and a suitable abrading grit-paste, is to grind out these irregular surfaces and provide the outer periphery of the body or article with a regular surface, so as to properly receive a suitable coating, 80 for instance a japan, and permit polishing of the same, for causing it to show a regular surface when finished.

An annularly arranged expansion-band 42 on the holder coacts with the cylindrical portion 39^e of the body. The expansion-band rotates with the holder. It is received in an annular recess 43 of the holder and is held therein by means of clips 44 secured to the holder by means of screws 45 for ready insertion or removal of the expansion-band. A pin 46 in the holder is received in a hole 47 in the expansion-band for causing rotation of the latter with the holder.

A spreader 48 is located between the proximate ends of the expansion-band and is provided with cams 49. The spreader is rockable in bearings 50, 51, on the holder, the bearing 51 being on a bearing-piece 52 releasably secured to the holder, as by screws 53. An arm 54 is fast to the shaft 55 of the spreader for turning the spreader and causing the cams 49 to contact the ends of the expansion-band for expanding the latter into contact with the cylindrical portion 39^e of the body 39, for clamping the body to the head. Upon rocking the spreader for disengagement of the cams with the expansion-band, the expansion-band will contract toward the axis of the holder and release the 110 body.

The expansion-band and cam-spreader may be removed from one holder and used on another holder whose base is of equal diameter, but whose apex end is of different 120 form, and is therefore interchangeable with holders whose bases are of equal diameters.

Reciprocating motion is caused between the article and the buffering-wheel. I prefer to have the article reciprocate as the buffering-wheel is rotated at high speed and requires comparatively high power to rotate the same at the speed required for the buffering operation.

For rotating and reciprocating the head I 125

provide a bevel-gear 61 fixed to a shaft 62 journaled in a bearing 63 on a bracket 64 of the carriage 35. The shaft 62 is suitably rotated as by having a knuckle-joint 65 connected therewith, the knuckle-joint having connection with a pluri-part shaft 66, comprising an inner member and an outer member, having spline-connection 67 between them for causing their combined rotation, and operated in suitable manner by a suitable driving agency.

The bevel-gear 61 meshes with a bevel-gear 70 which is fast on a hollow hub 71 journaled in a bearing 72 of the carriage. The hollow hub has a bevel-gear 73 fast thereon. A shaft 75 has spline-connection 76 with the hollow hub 71 for causing the shaft to rotate with the bevel-gears. A sleeve 77 surrounds the shaft, the shaft being rotatable in the sleeve and the sleeve sliding longitudinally in a bearing 78 on the carriage. The head-frame 79 is fixed to the sleeve, as by set-bolts 80 and slides on a guideway 81 on a bracket 82, extending from the carriage 35, the head-frame being thereby prevented from turning.

A bevel-gear 84 is fixed to the shaft 75, as by a set-bolt 85, the shaft and sleeve being relatively lengthwise positioned at the other end of the sleeve by means of the hub of the bevel-gear 84 and a collar 86 fixed to the shaft by a set-bolt 87. The outer end of the shaft is journaled in a bearing 88 in the head-frame. The bevel-gear 84 meshes with a pair of bevel-gears 93. Each of the bevel-gears 93 is fixed on a shaft 94 journaled in a bearing 95 of a head-yoke 96. The head 36 comprises a movable support 99 for the head, shown as a pivoted bearing-piece comprising a bearing 100 and arms 101. One of the arms 101 is pivoted, as by a shoulder-bolt 102 to one of the tines 103 of the head-yoke, the other of the arms 101 being secured, as by a set-bolt 104, to a pivot-shaft 105, pivoted in the other of the tines 101, and having an arm 106 rigidly secured thereto and extending therefrom, the arm arranged to carry weights 107 exemplified as suspended therefrom by means of a cable 108 and releasably received about the cable for adjusting the pressure of the head toward the buffing-wheel.

By these means a movable support for the head is arranged to swingingly support the head and to permit yielding of the head. An adjustable stop 110 is provided for determining the normal position of the head, the adjustable stop being shown in the form of a stop-bolt threaded in a lug 111 of the head-yoke and arranged to bear against a lug 112 extending from the movable support.

A shaft 114 is journaled in the bearing 100. The holders 41 are arranged to be interchangeably secured to the end of this

shaft, as by being provided with a bore 115, in which the end of the shaft is received, the holder being secured to the shaft by means of a set-bolt 116. A universal joint 117 is located between the shafts 114 and 94 for communicating rotation from the shaft 94 to the shaft 114 regardless of the angular positions of the movable member of the head. The articulation of the universal joint 117 is substantially in the plane of the pivotal axis of the pivoted member of the head.

When the holder is reciprocated in work position, the article 39 being buffed is moved toward the buffing-wheel 37 in a line parallel to the plane of movement of the carriage 35, contact being made by the article at or adjacent to its apex with the periphery of the buffing-wheel, contact with the buffing-wheel being made preferably at a point below the plane, parallel to the plane of movement of the carriage in which the axis of rotation of the buffing-wheel is located. This contact is preferably made with the body at one side of its principal axis, indicated by the dotted line 39^g.

As the article-head and body approach the buffing-wheel, the head and body yield to cause successive points on the outer face of the body to contact the buffing-wheel, the amount of this yield being determined by the outer peripheral form or face-contour of the body, the weighting of the head causing sufficient pressure of the head toward the buffing-wheel to cause proper abrasive or polishing action upon the body. The amount of this pressure may be regulated by the employment of more or less of the weights. The various positions of the head during the progressive movement thereof toward the buffing-wheel are exemplified by the dotted lines 39^h and 39^k in Figs. 6 and 7, the direction of movement of the head being in the direction of the arrow 39^m.

The bevel-gear 73 meshes with a bevel-gear 121 journaled on a stub-shaft 122 fixed in a bearing 123 in the carriage. A spur-gear 124 fast with the bevel-gear 121 meshes with a gear 125 on a crank-plate 126, which has a crank-pin 127 adjustable thereon toward and from the axis of the crank-plate, as by locating the same on a slide-block 128 adjustable in a T-slot 129 in the crank-plate, and clamped in position by a T-bolt 130 and nut 131.

A connecting-rod 133 is journaled in a bearing 134 about the crank-pin, the other end of the connecting rod being received in a bearing 135, in which it is suitably secured, as by a pin 136. The bearing 135 is on a bearing-piece 137, which has a bearing 138 thereon, in which a rod 139 is received, the rod being pivoted, as by a bearing 140, on a bolt 141 in lugs 142 of the head-frame. A spring 143 is received about the rod 139 be-

ween the bearing 138 and the bearing 140, the rod at the other side of the bearing 138 being provided with a collar 144 suitably secured thereto, as by a pin 145, for preventing movement of the bearing 138 off the rod. The reflector is held toward the buffing-wheel by means of the spring 143, which forms an additional resilient cushion for the head.

10 The eccentric or crank-pin 127 is adjustable toward and from the axis of the crank-plate for adjusting the length of the path of movement of the head-yoke, the head-yoke in this movement being slidable forward and back, that is, reciprocating with relation to the buffing-wheel.

Means are provided for moving the head a substantial distance toward and from the buffing-wheel for attachment or removal of the article being buffed. I prefer to accomplish this by manual means, and have instanced it as accomplished by means of a lever 151 provided with a handle 152, the lever being pivoted on a pin 153 on a slide 154, adjustable lengthwise of the guideways 84 on the saddle, for instance by means of having a screw-rod 156 secured thereto at 157, a nut 158 being threaded about the screw-rod and having a handle 159 thereon. 20 Lengthwise movement of the nut is prevented by having a fork 160 fast to the saddle, as by bolts 161, received in an annular groove 162 in the nut. Turning of the nut will move the slide 154 quickly 25 toward and from the position of the buffing-wheel, and when in proper adjusted position it is arranged to be clamped to the guideways by means of set-bolts 163.

The lever 151 has articulation at 164 with 40 a link 165 having an articulation at 166 with the carriage. When the lever 151 is swung upwardly and rearwardly on its pivot 153, its articulation 164 with the link 165 will move back with the lever and draw the 45 carriage, together with the operating parts and heads mounted thereon, away from the buffing-wheel, the assumed position of the lever in the latter relation being indicated in dotted lines in Fig. 4, which positioning 50 of the carriage may take place during continued automatic reciprocation thereof.

When the lever is manipulated for moving the head-part toward the buffing-wheel, the axis of its articulation 164 is below a right 55 line intersecting the axis of the pivot 153 and articulation 166, a stop 167 on the lever 151 being arranged to strike the link when in such relation, whereby the unintentional retraction of the carriage through the medium 60 of the link or lever is prevented, as this relation of the axes forms a locking relation against a strain tending to buckle the link and lever, and said head.

Adjustments are provided whereby the 65 article may be raised or lowered, as by

raising or lowering the table, as hereinbefore described; and whereby relative lateral adjustment may be accomplished between the article and the buffing-wheel, instanced as accomplished at the buffing-wheel by 70 means to be presently described, for adjusting the relations between the head and buffing-wheel for insuring the desired buffing contact therebetween and the necessary range of such contact; and means are 75 further provided whereby the article is yieldingly held toward the buffing-wheel, so as to move toward and from the buffing-wheel according to the contour of its outer periphery, as instanced by the weight mechanism hereinbefore described.

These adjustments accommodate various sizes and shapes of articles, and various sizes and shapes of articles are conveniently attached to the heads by having the holders 85 thereon interchangeable.

The lateral adjustment of the buffing-wheel, for adjusting the same laterally with relation to the principal axis of the body or article to be buffed, is preferably accomplished by axial adjustment of the buffing-wheel shaft 171. The buffing-wheel has a bore 172 received over the reduced end 173 of the shaft and is arranged to be clamped between flanges 174 by means of a clamp-nut 175, buffing-wheels of desired diameters and kinds being interchangeably clamped in place. The buffing-wheel shaft is journaled in bearings 176, and is rotated by a suitable rotating agency, for instance a pulley 177. 90 The pulley is arranged to be adjustably secured to the shaft, as by means of a set-bolt 178. When it is desired to adjust the buffing-wheel laterally, the set-bolt 178 is loosened, the shaft positioned endwise, and the pulley 105 secured thereto in adjusted position by resetting the set-bolt 178.

Having thus fully described my invention, what I claim as new and desire to secure by Letters Patent, is:

1. In a machine of the character described, the combination of an article-head comprising an article-holder, means for automatically reciprocating said article-head, means for yielding movement of said article-holder by pressure by a buffing-wheel upon the article carried thereby, whereby said article-holder automatically accommodates itself with relation to the buffing-wheel according to the contours of the form of the article carried by said article-holder, and an adjustable stop for limiting retraction of said article-holder from its yielding movement.

2. In a machine of the character described, the combination of an article-head comprising an article-holder, means for automatically reciprocating said article-head, means for yielding movement of said article-holder by pressure by a buffing-wheel 130

upon the article carried thereby, whereby said article-holder automatically accommodates itself with relation to the buffing-wheel according to the contours of the form 5 of the article carried by said article-holder, and means for adjusting the path of said reciprocating movement.

3. In a machine of the character described, the combination with a buffing-wheel, of an article-holder, means for automatically reciprocating said article-holder toward and from said buffing-wheel in a path oblique to the axis of rotation of said buffing-wheel, means for yielding movement 10 of said article-holder by pressure by a buffing-wheel on the article carried thereby, whereby said article-holder automatically accommodates itself with relation to the buffing-wheel according to the contours of 15 the form of the article carried thereby, and means for adjusting the lateral relation between said article-holder and said buffing-wheel whereby the contact between the article carried by said article-holder and said buffing-wheel is adjusted with relation to 20 the axis of rotation of said article-holder.

4. In a machine of the character described, the combination of an article-head comprising a resiliently yielding pivoted article-holder and means for simultaneously reciprocating said article-head and rotating 25 said article-holder.

5. In a machine of the character described, the combination of an article-head frame comprising a pair of article-heads ar- 30

ranged at angles with relation to each other, a resiliently yielding article-holder pivoted in each of said article-heads, and means for reciprocating said head-frame and rotating 40 said article-holders.

6. In a machine of the character described, the combination with a pair of buffing-wheels, of an article-head frame comprising a pair of article-heads comprising a pair of resiliently yielding pivoted 45 article-holders projected divergently toward said buffing-wheels at oblique angles with relation to the axes of rotation of said buffing-wheels, and means for reciprocating said head-frame in a path at substantial 50 right angles to said axes of rotation.

7. In a machine of the character described, the combination of an article-head comprising an article-holder, means for automatically reciprocating said article-head, means for yielding movement of said article-holder by pressure by a buffing-wheel upon the article carried thereby, whereby said head automatically accommodates itself with relation to the buffing-wheel according 60 to the contours of the form of the article thereon, and means for adjusting the path of said reciprocating movement.

In testimony whereof, I have hereunto signed my name in the presence of two sub- 65

EUGENE A. KUEN.
